Inventor,
Harold C. Jones

UNITED STATES PATENT OFFICE.

HAROLD C. JONES, OF CHICAGO, ILLINOIS; GEORGE H. JONES ADMINISTRATOR OF SAID
HAROLD C. JONES, DECEASED.

FENCEPOST.

Application filed August 18, 1923. Serial No. 658,046.

This invention relates to improvements in fence posts, and more particularly to posts used for supporting wires or wire mesh in the erection of fences and enclosures.

5 The object of the invention is to provide a strong and durable metallic post of proper design and dimensions to resist the strain placed upon it and further designed to permit the quick and easy attachment of the 10 wire to the posts.

A further object of the invention is to provide a practical method of erecting fences, which will enable the farmer or land owner to do the work, at less cost and without 15 the necessity of digging holes.

In the accompanying drawings, Figure 1 is a view in elevation of a section of fence erected with posts embodying the invention.

20 Figure 2 is a perspective view of a portion of a post showing the method of attaching the wire.

Figure 3 is a view in rear elevation of a section of a post, with a strand of wire attached.

Figure 4 is a perspective view of the anchor plate, and

Figure 5 is a cross sectional view of the post and anchor plate, the latter taken on line 5—5 of Figure 4.

The posts 1, are preferably lengths of rolled steel of T-section having pointed ends for penetrating the ground. Considering a post in its sectional contour it comprises a flange or cross web 2, adapted to extend parallel to or in the plane of the wire, and a transverse flange or base web 3, extending at right angles to the web 2. The webs are substantially of the same length and thickness, although both may be varied if desired. As a preferable formation for the web 3, a marginal enlargement or head 3^a is formed along its edge,—this for the obvious purpose of increasing the strength of the post and reducing the surface contact between wire and post, thereby minimizing the possibility of corrosion.

Along the marginal portions of the web 2, and on the side thereof toward the web 3, are rows of lugs or teeth 4, spaced apart uniformly by a distance of say, one-half inch, the teeth of each row being disposed opposite each other. Between the teeth are formed notches which aid in anchoring the

wire to the post as will presently be described. Extending centrally of the web 2, and along the front face thereof, is a comparatively shallow rib 5, extending the full length of the post.

The foregoing presents the preferred construction for the posts. In Figure 1 is illustrated the method of applying the wire to the posts, but in order that the same may be clearly understood, a single horizontal strand 6, indicating one of a plurality of 65 the horizontal wires that make up the woven type of fence wire shown in Figure 1.

The method of fastening the wires is the same regardless of the form of wire used, as the fastening takes place between the horizontal wires and the posts at the point of intersection. In setting the posts, the faces of the webs 2, are disposed in the line of the fence, so that the wire has contact with said face, although strictly speaking, the 75 contact is between the rib 5 and the wire, thereby affording a more positive connection to the post.

Assuming therefore, that a single wire is being stretched from post to post, the following method of fastening is followed. A supply of short lengths of relatively heavy wire which are bent to provide hooks at one end is provided. These form the fastening members 7. As the wire is stretched across the 80 post at the proper height above the ground, a fastener 7 is hooked over the edge of the web 2, with the hook end engaging between two lugs 4 immediately above (or below) the wire. The free end is then carried diagonally 85 across and over the wire, its extremity being bent over the opposite edge of the web 2, and between the lugs 4, just below (or above) the wire as shown in Figure 3. Each horizontal strand of wire is secured in like manner throughout the height of each post.

The post is further provided with an anchor plate 8 secured to the same near its lower end, and located so that its upper edge will reach approximately the depth that the post is to be driven into the ground. The purpose of the anchor plate is to give added stability, and to resist the strains tending to shift the position of the post in the ground, or cause it to lean in any direction. The 100 anchor plate is a substantially triangular piece of sheet metal with its shorter edge pointing downwardly. The plate is secured

against the flat side of the web 2 in the plane of the fence. The method of attaching the plate to the posts is as follows:

In forming the plate, a channel 8^a is provided which extends lengthwise thereof. The depth and width, as well as the sectional contour of the channel conforms generally to that of the web 3. Along either side of the channel are rows of holes 8^b. The rows and the holes of each row being spaced apart to conform with the spacing of the teeth 4 along the edges of the web 3. The channel 8^a is substantially the width of the bead 3^a along the edge of the web 3 and is adapted to fit over the same in the securing of the plate to the post. As clearly shown in Figure 5, the holes 8^b engage the teeth 4 adjacent the place of attachment, thus holding the plate against vertical displacement. To further secure the plate, the sides of the channel are bent in around the bead 3^a after the plate is fitted in place, this being accomplished by any suitable tool, as by blows with a hammer. Thus the anchor plate is secured to the post without the use of bolts, nuts or other permanent fastening means. Moreover, the method of attachment permits the lengthwise adjustment of the plate along the post, so that the depth to which the posts are to be driven, or the height of fence desired can be easily taken care of.

A post constructed in the manner described, combines the desirable features of strength, ease of fastening and securing the wire and adaptability for use under different conditions.

The fastening members can be easily supplied from a suitable grade of ordinary wire, and pliers and a hammer are the only tools necessary for cutting and shaping them, as well as securing them in place. Furthermore, the post being provided with teeth

throughout its length, the fastenings may be made at any point without stretching the wire to register with definitely spaced holes 45 or slots. Nor is the post weakened at its base by the drilling of holes to secure the anchor plates, and the adjustable feature is an advantage in locating the plates at the required distance from the end of the posts. 50

Having thus described the structure embodying the features of the invention, I claim:

1. A fence post consisting of a metal bar having a main web and a transverse web arranged in T-form, said transverse web having smooth marginal portions on its outer face and rows of lugs spaced apart along the inner edges thereof, and forming notches therebetween, adapted to be engaged by fastening members for the purpose described. 55

2. A fence post consisting of a metal bar of T-section, having a base web and a transverse web, the latter having a relatively smooth outer face slightly elevated along a 65 central longitudinal line and provided along the edges of its inner face with rows of projecting lugs spaced apart to form intermediate notches therebetween for the purpose described. 70

3. A fence post, consisting of a bar of T-section having a base web and a cross web, said cross web having a longitudinal central rib extending longitudinally along its outer face with smooth marginal surfaces on either 75 side thereof, and rows of lugs along the edges of the inner face of said cross web and spaced apart to form notches, the bases of which lie substantially in the plane of said inner face. 80

In witness whereof, I hereunto subscribe my name this 15 day of August, A. D. 1923.

HAROLD C. JONES.
